TRIMMING MACHINE

Archibald C. Smith, Rochester, N. Y., assignor to
 United Shoe Machinery Corporation, Paterson,
 N. J., a corporation of New Jersey

Application January 4, 1934, Serial No. 705,261

4 Claims. (Cl. 12—51)

This invention relates to trimming machines and is illustrated as embodied in a machine of the type disclosed in United States Letters Patent No. 1,963,071, granted June 19, 1934, upon 5 an application filed in the name of George Boulton.

In order to insure against careless or inexperienced operators cutting the side cover of a heel to which a heel-breast covering flap has been 10 attached while trimming lateral projecting margins of such flap flush with the respective breast edges of the heel in the above-mentioned machine which includes a cutter mounted for movement across a shearing edge of a breast gage, the machine illustrated herein is provided with a combined guard and gage having a lip constructed and arranged to engage a side of the heel adjacent to a corresponding breast edge of the heel and to cooperate with the breast gage in guiding 15 the projecting margin of the flap between the cutter and the shearing edge, the lip being positioned adjacent to and overlapping the leading portion of the cutter in the direction of travel of the heel past the cutter.

20 This and other features of the invention will be described as embodied in an illustrated machine and pointed out in the appended claims.

In the drawings,

Fig. 1 is a vertical sectional view taken through 25 the lower part of the operating head of the illustrated machine;

Fig. 2 is an enlarged plan view of the parts of the machine to which work is presented;

Fig. 3 is a perspective view of the parts of the 30 machine illustrated in Fig. 2; and

Fig. 4 is a perspective view showing the parts of the machine illustrated in Figs. 2 and 3 in the process of trimming one of the projecting margins of a covering flap secured to the breast of a 35 heel flush with a corresponding breast edge of the heel.

The illustrated machine is described with reference to trimming the projecting margins 20 (Fig. 4) of a covering flap 21 cemented to a Louis 40 heel 22 of a shoe 24 flush with a corresponding breast edge 26 of the heel. The machine with the exception of a combined guard and gage 28, is substantially identical with the machine which is disclosed in detail in the above-mentioned 45 United States Letters Patent No. 1,963,071, to which reference may be had for a more complete 50 understanding of the construction and operation of the machine.

The machine comprises a stationary gage or 55 block 30 provided with a flat upper face 32 and

a heel engaging face 34 (Fig. 3) which intersect to form a shearing edge 36. Mounted for orbital movement over surface 32 of the gage 30 is a hook-shaped cutter or cutting blade 38 having a cutting edge 40 (Fig. 2) which forms with the shearing edge 36 a throat into which a projecting margin 20 of the flap 21 is fed. In order to guide the heel 22 and the projecting margin 20 past the cutter 38, the breast of the heel is held against the upper portion of the face 34 of the 10 gage 30, the side of the heel to which the side cover of the heel has been applied and beyond which the margin 20 projects being held in sliding engagement with the bottom face of a lip 42 of the gage 28.

The lip 42 of the gage 28 is thus interposed 15 between the leading or forward portion of the cutter 38 and the side of the heel which is in engagement with the lip. The lip 42 may also be said to be positioned adjacent to the cutter 20 38 and in overlapping relation with the leading portion of the cutter in the direction of travel 44 (Fig. 3) of the heel 22 past the cutter. In the illustrated construction the gage 28 is cut away to provide a notch 46 (Fig. 3) within which the forward portion of the cutter 38 moves in an orbital path, the forward portion of the cutter at all times remaining within the notch. The lip 42 is very thin and the cutting edge 40 of the cutter 38 is located just above the upper face 50 of the 25 lip, the plane of movement of the cutter 38 intersecting the bottom of the notch. The lower face of the cutter 38 which terminates in the cutting edge 40 may, if desirable, engage the upper face 50 of the lip 42, although it is preferable to have such face slightly spaced therefrom.

30 By providing a gage 28 having the lip 42 there is no danger of the operator cutting into the side cover of the heel by accidentally moving the same into engagement with the leading portion of the cutter 38 as the heel 22 is moved in a tortuous path past the cutter 38.

The mechanism for operating the cutter 38 is identical with that disclosed in the above-mentioned United States Letters Patent No. 1,963,071 45 and will be briefly described. The cutter 38 is adjustably secured by a set screw 52 to a depending arm 54 of a cutter carrier 56 provided with a cylindrical recess 58 of suitable size to receive a roller bearing 60 which is rotatably secured to an eccentrically mounted pin 62 of a shaft 64. One end of the cutter carrier 56 is bifurcated to receive a block 66 which is mounted upon a pin 68 secured to the main frame of the machine. The shaft 64 may be operated by any suitable 50 55

source of power. As the shaft 64 is rotated it will be clear that an orbital movement is imparted to the cutter 38.

The shape of the orbit may be varied by changing the position of the cutter 38 relatively to the axis of rotation of the shaft 64. The gages 28, 30 may be initially adjusted relatively to the cutter 38 through mechanism which is identical with that disclosed in said United States Letters Patent No. 1,963,071 and it will therefore be unnecessary further to describe such mechanism in this application.

The trimming cut is started at the rear part of the shank portion 70 of the sole of the shoe in order to joint the lateral margins of the shank portion of the sole with the heel. In order to permit right and left projecting margins 20 of the flap 21 of the heel 22 to be progressively trimmed toward the tread end 72 of the heel the machine may be provided with right and left units.

Having described the invention, what I claim as new and desire to secure by Letters Patent of the United States is:

1. A trimming machine having, in combination, a stationary gage provided with a shearing edge, a cutting blade mounted for movement across said shearing edge to trim a projecting margin of a cover secured to one face of an article and projecting above a second face of the article, and a combined guard and gage which is provided with a lip having a surface constructed and arranged for engagement with said second face, said lip being constructed and arranged to overlap the leading portion of the blade in the direction of travel of the article guided by said first-named gage and said lip past the blade thereby to insure that the second face of the article is protected from contact with the blade during the trimming operation.
2. A trimming machine having, in combination, a stationary gage provided with a shearing edge, a hook-shaped cutter having a face which terminates in a cutting edge, means for moving the cutter across said shearing edge to trim a pro-

jecting portion of a covering flap secured to the breast of a heel which is moved past the cutter flush with one of the breast edges of the heel, and a combined guard and gage which is provided with a lip positioned adjacent to said face of the cutter and overlapping the leading end portion of said cutter in the direction of travel of the heel past the cutter, said lip being constructed and arranged for engagement with the side of the heel adjacent to said breast edge and cooperating with said stationary gage to guide the projecting portion of the flap between the cutting and the shearing edges.

3. A trimming machine having, in combination, a stationary gage provided with a shearing edge, a cutter having a cutting edge mounted for movement across the shearing edge to trim a projecting margin of a covering flap secured to the breast of a heel flush with a breast edge of the heel, a gage provided with a lip which is interposed between the leading portion of the cutting edge of the cutter and a side of the heel the projecting margin of the cover of which is guided by the gages, and means for operating the cutter.

4. A trimming machine having, in combination, a stationary gage provided with a shearing edge, a hook-shaped cutter provided with a cutting edge and mounted for movement in an orbital path to cause its cutting edge to travel across the shearing edge thereby to trim a lateral projecting margin of a covering flap secured to the breast of a heel flush with one of the breast edges of the heel, another gage provided with a notch constructed and arranged to include the leading portion of the cutter during its orbital movement and having a heel-guiding surface which is in overlapping relation with the cutter in the direction of travel of the heel past the cutter to guard the side of the heel from being accidentally scarred by the cutter, and means for operating the cutter in said path.

ARCHIBALD C. SMITH.
